HERMAN H. TOLL AND FRANK C. DUFF, OF CLARINDA, IOWA.

DRIVING MECHANISM FOR POWER WASHING MACHINES.

1,403,356.

Specification of Letters Patent. Patented Jan. 10, 1922.

Application filed October 12, 1919. Serial No. 330,303.

To all whom it may concern:

Be it known that we, HERMAN H. TOLL and FRANK C. DUFF, citizens of the United States of America, and residents of Clarinda,

5 Page county, Iowa, have invented a new and useful Driving Mechanism for Power Washing Machines, of which the following is a specification.

The object of this invention is to provide 10 an improved mechanism for transmitting power from a prime mover having a shaft rotating continuously in one direction to a follower adapted for alternating rotary motion.

15 A further object of this invention is to provide an improved construction and arrangement for driving mechanism for operating a washing machine of the cylinder type.

20 A further object of this invention is to provide improved means for reversing the direction of rotation of the follower device periodically.

25 A further object of this invention is to provide a reversing mechanism capable of adjustment or alteration by the substitution of a simple part to vary the extent of rotation of the follower between successive reversals.

30 Our invention consists in the construction, arrangement and combination of elements hereinafter set forth, pointed out in our claims and illustrated by the accompanying drawing, in which—

35 Figure 1 is a side elevation, partly in section, illustrating a power washing machine embodying our improved driving mechanism. Figure 2 is an end elevation of the same machine. Figure 3 is a detail section, 40 on an enlarged scale, taken through the reversing gear box substantially on the line 3—3 of Figure 2. Figure 4 is an elevation partly in section of the gear box with the reversing disk and outer plate removed, taken 45 substantially on the line 4—4 of Figure 3. Figure 5 is an edge view and Figure 6 an inner face elevation of the reversing disk detached. Figure 7 is a cross-section, on a further enlarged scale, on the line 7—7 of 50 Figure 4.

In the construction of the machine and mechanism as shown the numeral 10 designates a suitable frame, formed preferably of angle iron and rectangular in plan and 55 elevation. A platform 11 is carried by the lower portion of the frame 10 and a prime

mover 12, such as an electric motor, is mounted on said platform near one end of the frame, and has its armature shaft 13 extending longitudinally and centrally thereof. A cylinder shaped tank 14 is mounted in the upper portion of the frame 10 and is supported by trunnions 15 arranged centrally of its sides. The tank is provided with a sliding cover 16. Within the tank 14 a perforated sheet metal drum 17 is mounted and is adapted for rotary oscillation and also for continuous rotary motion on its longitudinal axis. The tank 14 is water-tight and is adapted to contain a suitable washing fluid, 60 and the drum is adapted to contain clothes to be washed or otherwise treated in the fluid, and is provided with suitable opening and closing means (not shown). Shafts 18, 65 one of which is shown in Figure 1, are fixed to end portions and centrally of the drum 17 and are journaled in the ends of the tank, and the shaft at one end projects through said tank and terminates in a clutch member 19. 70

A driving shaft 20 is arranged longitudinally at one end of the top of the frame 10 and journaled in a bearing 21 thereon, said shaft being provided at its inner end with a clutch member 22 adapted to engage at times 75 the clutch member 19 of the drum shaft. The driving shaft 20 is adapted for longitudinal movement in its bearing to effect engagement and disengagement of the clutch member 22 relative to the member 19, 80 such movement being controlled by a shifting lever 23. Feathered on the shaft 20 is a bevel gear in a housing 24, which is in mesh with and adapted to be driven by a bevel gear contained in a housing 25, the latter gear 85 being fixed to the upper end of a shaft 26. The lower end of the shaft 26 enters a gear housing 27 carried by the lower portion of the frame, at one side of the center thereof. A shaft 28 is arranged transversely and is 90 adapted to be driven from the motor shaft 13 by means of any suitable gearing contained in a housing 29, the other end of said shaft 28 entering the gear housing 27. A double 95 bevel gear is mounted for rotation in the housing 27, as on a stub shaft or spindle 30, and the outermost gear 31 thereof is in mesh with and adapted to be driven by a bevel pinion 32 fixed to the shaft 28. The innermost member 33 of the double gear is in 100 mesh with opposed bevel pinions 34, 35 loosely mounted on the shaft 26. The outer

side of the housing 27 is closed by a removable plate 36. A clutch block 37 is mounted on and fixed to the shaft 26 between the opposed bevel pinions 34, 35, and a double 5 pawl 38 is pivoted at its center, by means of a pin 39, to said clutch block, and has its ends extending toward and overlapping the hubs of the said bevel pinions. The hubs of the bevel pinions 34, 35 are formed with oppositely arranged lugs or shoulders 40 adapted to be engaged successively and selectively by the adjacent ends of the double pawl 38. The double pawl is arranged for oscillation in a plane passing through the 10 axis of the shaft 26, and is so arranged that when one end is in engagement with a lug or shoulder 40 of one of the pinions 34 or 35, the opposite end is clear from the lug or shoulder of the other of said pinions. In 15 this manner the shaft 26 is caused to rotate with that bevel pinion 34 or 35 with which the pawl is engaged, such engagement clutching said pinions selectively to the shaft. A tripping disk 41 is pivoted at its 20 center by a bolt 42 to the inner face of the housing plate 36, said pivot being opposite to the center of the pawl 38. The tripping disk 41 is formed with an inwardly projecting peripheral flange 43 which is unbroken 25 throughout a portion of the periphery and throughout the remaining portion thereof is notched to form ratchet teeth 44. The outstanding end of the pawl 38, that is to say the end which is not in engagement with the 30 hub of a bevel pinion 34 or 35, travels through an orbit, in the rotation of the shaft 26, which intersects the plane of the flange 43 and ratchet teeth 44. Each time the outstanding end of the pawl 38 is carried across 35 the plane of the teeth 44 it encounters the straight side of one of said teeth and produces a step forward in the rotation of the tripping disk 41 in one direction or the other, depending upon the direction in 40 which the shaft 26 is rotating at the time. This occurs until the disk 41 is rotated to the point where the outstanding end of the pawl engages the solid portion of the flange 43, whereupon said flange causes a tripping of 45 the pawl 38, or an oscillation on the pivot 39, forcing the then outstanding end in toward the shaft and the opposite end out. This movement of course has the effect of disengaging the pawl and shaft from the 50 bevel pinion 34 or 35 which had been the driver and engaging said members with the other of said bevel pinions, thus reversing the direction of rotation of the shaft 26, shaft 20, and drum 17, providing the clutch 55 members 22 and 19 are in engagement. Thus periodically the direction of rotation of the clothes drum is reversed, and the 60 number of revolutions in each direction between successive reversals depends upon the 65 number of teeth in the tripping plate 41.

It is plain that tripping plates may be provided having varying numbers of teeth, to provide the desired number of revolutions of the clothes drum between successive reversals. It is desirable to provide yielding 70 pressure devices acting upon the pawl 38 to hold it in either position in which it may be placed. For this purpose we have mounted a ball 45 in a recess in the block 37, said ball being held by a spring 46 against the outer 75 or inner face of one end portion of the pawl 38, and tending to hold that end either in or out as the case may be, but permitting oscillation of said pawl when sufficient pressure is applied to either end. 80

The tank 14 is also designed to be turned to upright position on its trunnions 15, the clutch member 19 of the drum shaft engaging a clutch member 47 of a driving mechanism designated generally by the numeral 85 48, located centrally of the frame on the platform 11. The driving mechanism 48 is operated from the motor shaft 13 and is controlled by a foot pedal 49, being designed to rotate the clothes drum 17 continuously 90 in one direction at a high rate of speed to dry the clothes therein by centrifugal force. This mechanism forms no part of our present invention but is illustrated, described and claimed in our companion application 95 filed September 5, 1919, Serial Number 321, 806, to which application reference hereby is made.

A plurality of pans 50 are carried by the lower portion of the frame 10 and are adapted to contain various kinds of washing fluids, such as suds, rinse and blue water. A centrifugal pump 51 is carried by the platform 11 and is adapted to be driven by the motor shaft 13 to raise water selectively 100 from the pans 50 to the tank 14 through a pipe 52, the operation of said pump being controlled by a clutch lever 53. This mechanism, however, forms no part of our present invention but is illustrated, described 105 and claimed in our companion application filed October 13, 1919, Serial Number 330, 304, to which application reference hereby is made. 110

Water is adapted to be drawn in turn 115 from each of the pans 50 to the tank 14 and the clothes to be washed are treated successively therein to the action of each kind of washing fluid, the drum 17 being driven in the manner and by the means hereinbefore described, in the horizontal position shown. After each such treatment the tank is turned to upright position and the fluid removed by rapidly rotating the drum through the mechanism 48, after which the fluid is allowed to return to its respective pan 50, a cock 54 being provided in one end of the tank for each of said pans. In this manner 120 the entire washing operation may be performed without the operator having to put 125 130

his hands in the water, or to handle the water or the wet clothing.

We do not desire to be understood as limiting ourselves strictly to the precise construction herein shown, as various modifications may be employed, within the scope of the appended claims, without departing from the spirit of our invention.

If desired the frame may be enlarged and 10 the tank 14, with contained drum, duplicated to any desired extent, all of the drums being driven from one source of power. This provides a machine for laundries doing 15 family washing, and permits keeping each washing separate from the others, thus obviating the mixing of clothes and effecting a saving of time in marking and sorting the same.

We claim as our invention—

20 1. A driving mechanism for power washing machines, comprising a power shaft, a bevel gear driven by said power shaft continuously in one direction, a follower shaft, opposed bevel pinions loosely mounted on 25 said follower shaft in mesh with said bevel gear, a clutch member mounted on and fixed to said follower shaft between the bevel pinions, a double pawl pivoted on said clutch member and adapted for selective operative 30 engagement with said bevel pinions, and a rotatable tripping member adapted to engage said pawl and shift the same after a predetermined number of revolutions of said follower shaft.

35 2. A driving mechanism for power washing machines, comprising a power shaft, a bevel gear driven from said power shaft continuously in one direction, a follower shaft, opposed bevel pinions loosely mounted 40 on said follower shaft in mesh with said bevel gear, a clutch member mounted on and fixed to said follower shaft between the bevel pinions, a pawl pivoted at its center on said clutch member, each of said bevel pinions 45 being formed with means for engagement by said pawl, whereby said pinions may be selectively clutched to said follower shaft, and a tripping plate rotatably mounted and formed with a plurality of notches adapted 50 to permit passage of said pawl in successive revolutions of said follower shaft and also formed with means adapted for subsequent engagement with and oscillation of said pawl.

55 3. A driving mechanism for power washing machines, comprising a power shaft, a bevel gear driven from said power shaft continuously in one direction, a follower shaft, opposed bevel pinions loosely mounted on 60 said follower shaft in mesh with said bevel gear, a clutch member mounted on and fixed to said follower shaft between said bevel pinions, a pawl pivoted between its ends on 65 said clutch member and adapted for selective operative engagement with said bevel

pinions, and movable means independent of said bevel gear for oscillating said pawl to reverse its relation to said pinions.

4. A driving mechanism for power washing machines, comprising a power shaft, a bevel gear driven from said power shaft continuously in one direction, a follower shaft, opposed bevel pinions loosely mounted on said follower shaft in mesh with said bevel gear, a clutch member fixed to said shaft between said bevel pinions, a pawl pivoted between its ends on said clutch member and adapted for selective operative engagement with said bevel pinions, movable means independent of said gear for oscillating said pawl periodically to reverse its relation to said pinions, and a yielding pressure device tending to hold said pawl in either position.

5. A driving mechanism for power washing machines, comprising a power shaft, a bevel gear driven from said power shaft continuously in one direction, a follower shaft, opposed bevel pinions loosely mounted on said follower shaft in mesh with said bevel gear, a clutch member fixed to said follower shaft between said bevel pinions, a pawl pivoted between its ends on said clutch member and adapted for selective operative engagement with said bevel pinions, 90 and rotatable means operative through the rotation of said follower shaft for engaging and reversing the position of said pawl.

6. A driving mechanism for power washing machines, comprising a power shaft, a bevel gear driven from said power shaft, a follower shaft, opposed bevel pinions loosely mounted on said follower shaft in mesh with said bevel gear, a pawl pivoted at its center midway between and adapted for selective 100 operative engagement with said bevel pinions, and a tripping member adapted to engage the non-operative end of said pawl and shift the same after a predetermined number of revolutions of said follower shaft.

7. A driving mechanism for power washing machines, comprising a power shaft, a bevel gear driven from said power shaft, a follower shaft, opposed bevel pinions loosely mounted on said follower shaft in mesh with said bevel gear, a pawl pivoted at its center midway between and adapted for selective operative engagement with said bevel pinions, and a tripping member formed with a peripheral flange provided with a series of notches throughout a portion of its length, the outstanding end of said pawl being adapted to engage in said notches successively and move said tripping member a step rotatively for each revolution of the 115 follower shaft until said pawl encounters the solid portion of said flange, which encounter produces an oscillation of said pawl and reversal of movement of said follower shaft and tripping member.

8. A driving mechanism for power washing machines, comprising a power shaft, a bevel gear driven from said power shaft, a follower shaft, opposed bevel pinions loosely mounted on said follower shaft in mesh with said bevel gear, a pawl pivoted at its center midway between and adapted for selective operative engagement with said bevel pinions, and a removable and replaceable tripping member mounted for rotation and formed with a peripheral flange having a series of notches throughout a portion of its

length, the outstanding end of said pawl being adapted for successive engagement in said notches to move said tripping member 15 to a position for engagement of the solid portion of said flange by said pawl to effect an oscillation and reversal of said pawl.

Signed at Clarinda, in the county of Page and State of Iowa, this 8th day of September, 1919.

HERMAN H. TOLL.
FRANK C. DUFF.
